[57] CLAIM

The ornamental design for a combined pointing stick and surrounding keycap for use in a computer keyboard, as shown and described.

DESCRIPTION

FIG. 1 is a perspective view of the combined pointing stick and surrounding keycap, showing my new design; FIG. 2 is a rear elevational view thereof;

FIG. 3 is a front elevational view thereof;

FIG. 4 is a right side, elevational view, the left side being substantially a mirror image thereof;

FIG. 5 is a bottom plan view thereof; and,

FIG. 6 is a top plan view thereof shown disposed in a computer keyboard wherein the surrounding keys are shown in broken lines for illustrative purposes only and form no part of the claimed design.

FIG. 2

FIG. 3

FIG. 4

FIG. 5

FIG. 6
